UNITED STATES PATENT OFFICE

160,188

MOTION-PICTURE CAMERA

Frank Lustig and Harris E. Nelson, Chicago, Ill.,
assignors to Revere Camera Company, Chicago,
Ill., a corporation of Delaware

Application September 22, 1949, Serial No. 5,138

Term of patent 14 years

(Cl. D61—1)

To all whom it may concern:

Be it known that we, Frank Lustig and Harris E. Nelson, citizens of the United States, residing at Chicago, State of Illinois, have invented a new, original, and ornamental Design for a Motion-Picture Camera, of which the following is a specification, reference being had to the accompanying drawing, forming a part hereof.

Fig. 1 is a side elevational view of a motion-picture camera showing our new design;

Fig. 2 is a front elevational view thereof;

Fig. 3 is a top view thereof;

Fig. 4 is a side elevational view of the opposite side to that shown in Fig. 1;

Fig. 5 is a rear elevational view thereof, and

Fig. 6 is a bottom view thereof.

We claim:

The ornamental design for a motion-picture camera, as shown.

FRANK LUSTIG.
HARRIS E. NELSON.
